DEVICE FOR SHARPENING KNIVES OR
THE LIKE

Ray D. Parsons, Eldora, Iowa

Application May 5, 1932. Serial No. 609,432

4 Claims. (Cl. 76—86)

The principal object of my invention is to provide an efficient strong sharpener for cutlery or the like that will successfully and evenly sharpen and bevel both sides of the cutting edge at the same time.

A further object of this invention is to provide a device for the sharpening of knives or the like that may be easily and quickly adjusted to give various bevels to the cutting edge.

10 A still further object of my invention is to provide a sharpener for cutlery that quickly sharpens a blade or like by natural movement of the same through the sharpener.

A still further object of this invention is to provide a sharpener for cutlery or the like that has easily removable sharpening bars.

Still further objects of my invention are to provide a device for sharpening knives and the like that is economical in manufacture, durable 20 in use and safe in operation.

These and other objects will be apparent to those skilled in the art.

My invention consists in the construction, arrangement and combination of the various parts 25 of the device, whereby the objects contemplated are attained as hereinafter more fully set forth, pointed out in my claims and illustrated in the accompanying drawing, in which:

Fig. 1 is a side view of my complete invention 30 ready for use.

Fig. 2 is a top plan view of my sharpening device.

Fig. 3 is a rear end view of the device and shows an angle at which the cutting bars may be adjustably set relative to each other.

Fig. 4 is a front end view of the complete invention and shows the position of the sharpening bars when a comparatively blunt cutting edge is desired.

40 Fig. 5 is a cross sectional view of the invention taken on line 5—5 of Fig. 2 and more fully illustrates the construction of the invention.

Fig. 6 is a cross sectional longitudinal view of the sharpening bars or files taken on a line where 45 these two members come in close proximity to each other.

Fig. 7 is a side plan view of a portion of one of the file bars showing the curved construction of its cutting surface for delivering the diagonal 50 cut to the bevel of the blade to be sharpened.

There are many cutlery sharpening devices on the market but the chief objections to these devices are that they are hard and dangerous to operate and do not evenly bevel both sides of 55 the instrument to be sharpened.

Furthermore these devices unevenly sharpen the length of the blade. I have overcome such disadvantages by providing a device capable of easily and accurately beveling a blade throughout its entire longitudinal length.

60 Referring to the drawing I have used the numeral 10 to designate the base portion of the invention. This base portion is in the form of an elongated strip of metal having its front end portion 11 bent vertically upwardly and its rear end portion 12 bent vertically downwardly, as shown in Fig. 1. The numeral 13 designates a flat end member secured by any suitable means to the outside of the portion 12. This member 13 extends upwardly beyond the plane of the base member 10 and is parallel with the portion 11. The numerals 14 and 15 designate two spaced apart straight jaw members. These jaw members 14 and 15 which are of metal bar construction are pivoted at the lower portion of each 70 of their ends to the members 11 and 12, as shown in the drawing. By this arrangement the upper marginal edges of the jaws 14 and 15 may be swung toward or away from each other. The numerals 16 and 17 designate two rod ends extending toward the central portions of the two jaw members 14 and 15, respectively, as shown in Fig. 5. These members 16 and 17 are secured by any suitable means to the central portion of the member 10. Threaded onto the free end 80 portions of each of the members 16 and 17 is an elongated nut 18 having its outer end portion rounded for engagement with the outer side of one of the jaw members. By this construction, the rotation of the nuts 18 will adjustably position the two jaw members 15 and 14 relative to each other. The numeral 19 designates a notch cut in the portion 11 and in line with the space between the two jaw members.

85 The numeral 20 designates a similar notch cut in the portion 13, as shown in Fig. 3. These notches permit the instrument to be sharpened to be placed and drawn between the two jaw members 14 and 15. Resting on the inner side of the jaw 14 is a cutting bar 21. A similar bar 22 engages and rests upon the inner face of the jaw 15. These sharpening bars may be in the form of cutting files, such as shown in Fig. 7 and having their cutting edges of curved construction for delivering the diagonal cut to the bevel of the 105 blade as the same is pulled between them. For best results it is recommended that these curved cutting edges of the two members 21 and 22 be staggered relative to each other, as shown in Fig. 6. Such a positioned arrangement not only more 100

successfully bevels the blade to be sharpened but encourages the blade to seek the dead center bottom line between the two members and eliminates excessive downward pressure on the blade 5 being drawn longitudinally on the blades between the members 21 and 22.

In Fig. 1 I show an instrument such as a knife 23 being drawn between the two members 21 and 22 for sharpening purposes. In each of the jaw 10 members 14 and 15 are two spaced apart transversely extending slots 24. Extending through each of these slots 24 is a cap screw 25 threaded into the sharpening bars, as shown in Fig. 2. The 15 lengths of these cap screws are such that their forward ends do not pass beyond the inner side of the bar to which they are threaded. By this arrangement the bars or files 21 and 22 may be adjustably positioned and held relative to each other.

20 By placing one of the bars lower than the other as shown in Fig. 5, a desirable result is obtained. Also the bars or files may be changed relative to each other to provide new wearing surface. By the cap screws 25 being threaded into the 25 central line portion of the members 21 and 22, those members may be completely turned and positioned so that their lower side edges become their top side edges. Also by making both sides of the members 21 and 22 cutting sides, as shown 30 in Fig. 6, they may be rotated to give additional cutting and wearing surfaces. By such an arrangement a tool of long life is assured. After the members 21 and 22 have been desirably positioned, the cap screws 25 should be tightened to 35 rigidly hold the members against accidental and undesirable vertical movements made possible by the slots 24.

One of the desirable advantages of the 40 construction of my device is that it need not be clamped to a supporting surface. By providing the downwardly extending end 12, a hook portion is provided which may be positioned over the edge of a table or supporting surface. As the instrument 23 is drawn away from the end 12, 45 there is no possibility of undesirable movement of the tool.

By rotating the nuts 18, the jaws 14 and 15 supporting the bars may be adjustably positioned relative to each other for obtaining various desirable bevels on the cutting blade. Due to the rugged construction of my invention it may be successfully used to sharpen heavy instruments 50 such as meat cleavers and the like.

From the foregoing it will readily be appreciated that I have provided a very desirable instrument for the successful beveling and sharpening 55 of cutlery.

Some changes may be made in the construction and arrangement of my improved device for 60

65

70

75

sharpening knives or the like without departing from the real spirit and purpose of my invention, and it is my intention to cover by my claims any modified forms of structure or use of mechanical equivalents which may be reasonably included 80 within their scope.

I claim:

1. In a device of the class described, a base member, two jaws pivoted at their lower end portions to said base member, a sharpening bar resting on each of said jaws, a rod secured to said base member and extending toward the central portion of one of said jaws, a second rod secured to said base member and extending toward the central portion of the other jaw, and a nut 85 threaded on each of said rods capable of engaging the jaw adjacent to it.

2. In a device of the class described, a base member, two jaws pivoted at their lower end portions to said base member, a sharpening bar resting on each of said jaws, a rod secured to said base member and extending toward the central portion of one of said jaws, a second rod secured to said base member and extending toward the central portion of the other jaw, and a nut member 95 having a rounded end threaded on each of said rods capable of having its rounded end engaging the jaw adjacent to it.

3. In a device of the class described, an elongated base member having a downwardly extending 105 hook portion at one end, two elongated jaw members each hingedly secured at its lower side to said base member extending longitudinally to the edge of the instrument to be sharpened and parallel of the longitudinal axis of said elongated 110 base member, a sharpening elongated bar member secured on the inner side of each of said jaw members and extending parallel with the jaw member to which it is secured, a rod secured to said base member and extending toward the central outer portion of one of said jaws, a second rod secured to said base member and extending toward the central outer portion of the other jaw, and an elongated nut threaded on each of said rods capable of engaging the jaw adjacent to it. 120

4. In a device of the class described, a base member, two jaws pivoted at their lower portions to said base member, a sharpening bar resting on each of said jaws, a rod member and adjusting nut thereon extending between said base member and the central portion of one of said jaws capable of 125 adjustably positioning the jaw at various positions relative to said base member, and a second rod member and adjusting nut thereon extending between the base member and the central portion of the other jaw capable of 130 adjustably positioning that jaw at various positions relative to said base member.
